(57) **CLAIM**

The ornamental design for a wheelchair frame, as shown and described.

DESCRIPTION

1.1 is a perspective view of a wheelchair frame embodying our new design as attached to an exemplary wheelchair; 1.2 is a front perspective view thereof independent of the exemplary wheelchair;

1.3 is a top perspective view thereof;

1.4 is a left side elevation view thereof;

1.5 is a right side elevation view thereof;

1.6 is a top plan view thereof; and

1.7 is a front elevation view thereof.

The broken line showing of the wheelchair is provided for the purpose of illustrating environmental structure and forms no part of the claimed design.
